UNITED STATES PATENT OFFICE.

RICHARD EVANS ELLETT, OF LONDON, ENGLAND.

DESIGN FOR A DANCING-DOLLS TOY.

Application filed August 13, 1928. Serial No. 27,802. Term of patent 7 years.

To all whom it may concern:

Be known that I, RICHARD EVANS ELLETT, a subject of the King of Great Britain, residing at London, England, have invented a new, original, and ornamental Design for a Dancing-Dolls Toy, of which the following is a specification, reference being made to the accompanying drawings, forming part thereof.

Figure 1 is a view from one side and Figure 2 a view from the opposite side of a dancing dolls toy showing my new design.

I claim:—

The ornamental design for a dancing dolls toy as shown.

RICHARD EVANS ELLETT.
